(57) **CLAIM**

The ornamental design for a cover for cancer cell observation camera, as shown and described.

DESCRIPTION

FIG. 1 is a front view of a cover for cancer cell observation camera of the present invention.

FIG. 2 is a rear view of the cover for cancer cell observation camera of FIG. 1.

FIG. 3 is a top plan view of the cover for cancer cell observation camera of FIG. 1.

FIG. 4 is a bottom plan view of the cover for cancer cell observation camera of FIG. 1.

FIG. 5 is a right side view of the cover for cancer cell observation camera of FIG. 1.

FIG. 6 is a left side view of the cover for cancer cell observation camera of FIG. 1.

FIG. 7 is a perspective view showing the top of the cover for cancer cell observation camera of FIG. 1.

FIG. 8 is a perspective view showing the bottom of the cover for cancer cell observation camera of FIG. 1.

FIG. 9 is a sectional view taken along line 9-9 of FIG. 1.

FIG. 10 is an enlarged view showing a portion of FIG. 9 defined by line 10-10.

FIG. 11 is a perspective view showing the bottom of the cover for cancer cell observation camera of FIG. 1 in a state of use; and,

FIG. 12 is a perspective view showing the top of the cover for cancer cell observation camera of FIG. 1 in a state of use. The dot-dash lines represent the bounds of the claim, while all other broken lines are directed to environment and are for illustrative purposes only. The broken lines form no part of the claimed design.

1 Claim, 12 Drawing Sheets
